UNITED STATES PATENT OFFICE.

JOHN J. BOUCHARD AND WILLIAM F. ENSOR, OF BRADFORD, PENNSYLVANIA, ASSIGNORS TO THEMSELVES, BURT H. COLLINS, AND EARLE C. EMERY, OF BRADFORD, PENNSYLVANIA.

TROLLEY-STAND.

SPECIFICATION forming part of Letters Patent No. 738,602, dated September 8, 1903.

Application filed December 18, 1902, Serial No. 135,701. (No model.)

To all whom it may concern:

Be it known that we, JOHN J. BOUCHARD and WILLIAM F. ENSOR, citizens of the United States, and residents of Bradford, in the county of McKean and State of Pennsylvania, have invented a new and Improved Trolley-Stand, of which the following is a full, clear, and exact description.

Our invention relates to improvements in stands for the trolley-poles of electrically-driven railway-cars.

In the present invention we seek to produce a simple and substantial construction of the mechanism constituting the bearing around which the pole may swing or turn on a vertical center, said mechanism being so designed as to minimize the friction and wear on the working surfaces, to turn easily and freely without lubrication, and to exclude the entrance of dust and dirt from the working parts. We also seek to produce a construction which provides for the secure attachment of the pole to the pole-socket in a way to relieve the strain on the pole-clamp and to allow the ready interchange of different poles.

Further objects and advantages of the invention will appear in the course of the subjoined description, and the novelty will be defined by the annexed claims.

Reference is to be had to the accompanying drawings, forming a part of this specification, in which similar characters of reference indicate corresponding parts in all the figures.

Figure 1 is a side elevation of a trolley-stand constructed in accordance with our invention. Fig. 2 is a plan view thereof. Fig. 3 is a longitudinal central section through the stand on the line 3-3 of Fig. 2. Fig. 4 is an enlarged sectional view through one of the antifriction-bearings, and Fig. 5 is a plan view of said bearing.

5 designates a base-plate which is provided with a central threaded opening 6, in which is screwed the lower threaded end 7 of a short vertical post 8. This post is equipped with one or more antifriction-bearings 9 of the type shown more particularly by Figs. 4 and 5, and these bearings support a shell or casing 10, adapted to inclose the bearings. The shell

or casing is provided with horizontal arms 11, which project from opposite sides thereof, said arms being integral with the casing. The arms support or carry a horizontal pivotal shaft 12, on which is mounted a yoke 13, 55 said yoke being cast in one piece with a tube or sleeve 14, adapted to form a socket for the trolley-pole 15, and the arms of said yoke 13 are provided with depending lugs 16. To these arms are pivoted the rods or bolts 17, 60 which lie on opposite sides of the casing or housing 10 and have their other ends fastened to a cross-head 18, the same being slidably fitted on a guide-tube 19, which is secured in a boss 20, cast in one piece with the casing or 65 housing. The cross-head 18 is pressed in one direction by a strong coiled spring 21, loosely fitted on the guide tube or rod 19, and one end of this spring is seated against the boss 20, while its other end acts against the slideable cross-head 18. The movement of the cross-head in one direction is limited by a nut 22, screwed on the outer end of the guide tube or rod 19, and against this stop-nut acts a 70 check-nut 23, also screwed on the guide-stem 75 afforded by the tube or rod 19.

The tube 14 is provided with a socket 24, and said tube is also split or divided for a part of its length, as indicated at 25 in Fig. 1, thereby forming a pair of coöperating 80 gripping-jaws 26 at the free ends of said tube 14. The slit or division 25 does not extend the full length of the socket 24 in the tube 14, and the jaws 26 of said tube are provided on opposite sides with the lugs 27, which are 85 disposed in pairs. The pairs of lugs on opposite sides of the divided tube are coupled by bolts 28, having suitable nuts 29, and by tightening these nuts the bolts are adapted to draw the lugs together in a way to compress the jaws 26 on the trolley-pole 15. This pole is fitted in the socket 24 of the tube to extend beyond the inner end of the division 25, and the pole thus has a solid bearing against the tube 14, which relieves the bolts 90 28 of considerable strain. The nuts may be readily loosened to release the gripping-jaws from the pole 15, which can be easily withdrawn, after which another pole can be inserted in the socketted tube and confined 100

therein by the clamp, consisting of the jaws and the bolts.

Each antifriction-bearing 9 is constructed as indicated by Figs. 4 and 5, in which 30 designates a cylindrical shell having an internal conical track-surface 31. A tubular bushing 32 is fitted in this shell concentric therewith, and said bushing is provided with an external track-surface 33, which is in opposing relation to the surface 31 of the cylindrical shell. An adjusting-ring 34 is screwed in the upper open end of the cylindrical shell 30, and said ring is provided with an inner conical surface 35. The ring 34 is made fast 70 with the shell 30, and a similar ring 36 is made fast with the bushing 32 by screwing it on the male-threaded upper end of the bushing, said ring 36 having an external conical surface 37, which is in opposing relation 80 to the internal conical surface 35 of the ring 34. An external gear-ring 38 is fitted on the bushing to rest on the ledge formed by the track-surface 33, and this gear-ring is clamped in place by the track-ring 36, which is fixed 85 to the bushing 32. An internal gear-ring 39 is fitted on the ledge afforded by the track-surface 31 of the cylindrical casing, and it is held in place by the adjusting-ring 34, which is screwed within the casing 30, the gear-rings 38 39 being concentric and disposed in 90 opposing relation.

40 designates a series of spindles, which carry the conical bearing-rollers 41 42, the rollers 41 being disposed between the track-surfaces 31 33 of the casing and the bushing, while the rollers 42 are confined between the track-surfaces 35 and 37 of the adjusting-rings 34 and 36, which are attached to the casing and the bushing, respectively. These 95 spindles 40 are also provided with the gear-pinion 43, which mesh with the gear-rings 38 and 39 of the bearings, thus positively turning the spindles and the friction-rollers carried thereon.

45 The lower bearing 9 is fitted to the short post 8 by slipping the bushing 32 thereon, and this bushing rests upon a washer 44, below which is arranged a packing material 45, which in turn rests upon another metallic washer 47, that engages directly with the top face of the base, the latter having a boss 5^a, which extends into the lower open end of the surrounding casing 10. The metallic washers and the packing fit snugly within the lower 100 part of the cylindrical casing 10, so as to exclude the admission of dust and moisture to the bearing. On top of the lower bearing 9 is seated a spacing ring or collar 48, which incloses suitable metallic washers 49 and 50, 105 and on the upper washer 50 and the spacing-ring 48 rests the bushing and shell of the upper bearing 9. The adjusting-rings 34 36 of this upper bearing 9 are provided with notches or sockets 51, and the casing 10 is provided 110 with an internal ledge or shoulder 52, the latter being disposed near the upper part of said casing. This ledge or shoulder is provided

with depending studs 53, adapted to fit in the sockets 51, which are provided in the adjusting-ring 34, forming a part of the upper bearing 9, thus making the casing or shell 10 fast with certain parts of said upper bearing. The casing or shell 10 is open at its upper end and externally threaded to receive a cap-nut 54, which is screwed detachably to the 125 casing.

The post 8 extends through the two bearings 9 and into the upper part of the casing 10, and on the upper bearing 9 rests a spacing-sleeve 55, the upper edge of which is engaged by a metallic washer 56, adapted to support a packing material 57 and another metallic washer 58. On the upper extremity of the post 8 is screwed a clamping-nut 59, which bears against the washers 56 58 and the 130 packing material and exerts pressure on the spacing-sleeve 55, the latter resting on one of the adjusting-rings of the upper bearing 9.

It will be observed that the two bearings 9 have their bushings 32 fitted on the post 8, and the nut 59 is arranged to clamp the central parts of these bearings 9 firmly to the posts, while the shells 30 of the bearings are loosely supported on and around the posts, so as to rotate freely thereon. The shells 30 of the 140 upper and lower bearings are fitted snugly in the external casing or housing 10, which is made fast with the upper bearing, and this external casing or housing is supported by the antifriction-bearings and the post in a 145 way to raise the lower edge of the casing or housing 10 from engagement with the base-plate 5, thus minimizing the friction and wear on the working parts. The employment of the packing materials 45 57 in the 150 upper and lower parts of the casing 10 exclude the admission of dust and moisture to the antifriction-bearings, and the revoluble support for the pole 15 is free to turn on a 155 vertical axis, owing to the presence of the 160 roller-bearings, which do not require lubrication. The spring 21 acts through the cross-head 18 and the rods 17 to pull on the depending members 16 of the pivoted yoke, which forms a part of the pole-socket, and 165 the pole 15, together with the tension devices therefor, are supported wholly by the casing or housing 10, which is free to turn on the vertical axis afforded by the stationary post 8.

Having thus described our invention, we 170 claim as new and desire to secure by Letters Patent—

1. In a trolley-stand, the combination of a non-revoluble post, a casing provided with an inwardly - extending shoulder and fitted 175 loosely around the post, an antifriction-bearing having a member clamped to said post, and an external member revoluble freely within said casing, said bearing also having an interposed roller - supported wear-ring 180 which is made fast with the shoulder of the casing, the entire casing being supported by the parts of the antifriction-bearing.

2. A trolley-stand having a base provided

- with an upstanding shoulder, a post fixed to and extending above the base, spaced antifriction-bearings fitted to said post one above the other and each having a roller-supported 5 external member, a casing inclosing said bearings and the post and provided with an inwardly-extending shoulder arranged to rest on the upper bearing, and a dust-excluding packing supported by the upper part of the 10 post and fitted within the casing above the bearing-shoulder therein.
3. The combination of a casing provided with an inwardly-extending shoulder, a cap fixed removably to said casing above the 15 shoulder therein, a base, a post extending from the base into the casing above the shoulder therein, antifriction-bearings mounted on the post within the casing and having engagement with said shoulder, and dust-excluding 20 washers fixed to the post, one of said washers lying below the bearings and the other washer being disposed in the casing between the shoulder thereof and the removable cap.
4. In a trolley-stand, the combination of a 25 base-plate, a fixed post, an antifriction-bearing having one member clamped to said post and inclosed within an external rotary member, a revolute casing supported by a part of said bearing, and dust-excluding washers 30 attached to the post and housed snugly within the casing on opposite sides of the antifriction-bearing therein.
5. A trolley-stand having a base-plate, a post fixed thereto, an antifriction-bearing fitted to said post, washers and packing layers
- fitted to the post on opposite sides of said bearing, a casing or housing arranged to inclose the bearing, the washers and the packing layers and having connection with a revolute member of the bearing to be supported 40 thereby, and a pole-support mounted on said casing to turn therewith.
6. A trolley-stand having a base, a post fixed thereto, a series of antifriction-bearings fitted to said post and each having a revolute shell, 45 packing layers fitted to the post, means for clamping the packing layers and certain elements of the antifriction-bearings to the post, a casing or housing supported by a revolute shell of the upper bearing and inclosing said 50 bearings and the packing layers, and a pole-support mounted on said casing.
7. A trolley-stand having a base, a post fixed thereto, a casing provided with an internal ledge or shoulder and with a removable cap-nut, antifriction-bearings fitted to the post within said casing, means connecting one of said bearings with the internal ledge or shoulder of the casing, means for clamping certain parts of the bearings to the post, and a pole- 60 support carried by the casing.
- In testimony whereof we have signed our names to this specification in the presence of two subscribing witnesses.
